DESCRIPTION

U.S. PATENT DOCUMENTS

The ornamental design for an interface unit for computer, as
shown and described.

D331,395 S * 12/1992 Lou D14/433
D340,059 S * 10/1993 Wetzel et al. D14/433
D345,980 S 4/1994 Scheid et al. D14/191
D361,332 S * 8/1995 Scheid et al. D14/191
D366,047 S * 1/1996 Rak et al. D14/242

FIG. 1 is a front elevational view of an interface unit for

computer showing my design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is an enlarged right side view elevationa thereof; and,

FIG. 8 is a perspective view thereof.

Portions in broken lines are for illustrative purpose only and
form no part of the claimed design.
